CLAIM

The ornamental design for a hanger for collapsible tubes, substantially as shown and described.

DESCRIPTION

FIG. 1 is a top front perspective view of a hanger for collapsible tubes showing my new design;

FIG. 2 is a front elevational view thereof;

FIG. 3 is a rear elevational view thereof;

FIG. 4 is a left side elevational view thereof, the right side being substantially a mirror image thereof;

FIG. 5 is a bottom plan view thereof; and

FIG. 6 is a top plan view thereof.
